(Continued)Primary Examiner — Eric Goodman*Assistant Examiner* — Amy Wierenga(74) Attorney, Agent, or Firm — James E. Howard; Andre Pallapies(57) CLAIM

The ornamental design for a display for dishwasher, as shown and described.

DESCRIPTION

FIG. 1 is a front view of a display for dishwasher showing our new design; and,

FIG. 2 is a perspective view thereof.

The broken lines represent unclaimed subject matter and form no part of the claimed design.

1 Claim, 2 Drawing Sheets
